UNITED STATES PATENT OFFICE.

FRANK EVANS HOLT, OF VANCOUVER, CANADA.

DUST-GUARD.

No. 827,728.

Specification of Letters Patent.

Patented Aug. 7, 1906.

Application filed February 9, 1906. Serial No. 300,274.

To all whom it may concern:

Be it known that I, FRANK EVANS HOLT, of Vancouver, county of New Westminster, Province of British Columbia, Dominion of Canada, have invented certain new and useful Improvements in Dust-Guards; and I do hereby declare that the following is a full, clear, and exact description of the invention, such as will enable others skilled in the art to 10 which it appertains to make and use the same.

This invention relates to improvements in dust-guards for car-axle journal-box, and has special reference to a device of this class which is adapted to be placed in the ordinary 15 standard journal-box.

Among the advantages attained by this invention is the production of a dust-guard embodying features of efficiency, durability, and simplicity which insure the exclusion of 20 dust and retention of oil and render the guard accommodative to car-axle boxes of standard form.

The object of the invention is to provide a device of the class described which is formed 25 of few parts so connected and arranged as to be practically inseparable when the parts are in use.

The invention consists in the combination and arrangement of parts which are shown in 30 the accompanying drawings, all as hereinafter more fully described, and particularly pointed out in the claims, it being understood that said drawings illustrate the preferred construction, which may be departed from in 35 the form, proportion, and minor details of parts therein shown within the scope of the claims without sacrificing any of the advantages of the invention.

In the accompanying drawings, in which 40 similar characters of reference indicate corresponding parts in all the views, Figure 1 is a longitudinal sectional view taken through a car-axle box, showing the improved dust-guard in position in the pocket provided 45 therein. Fig. 2 is a vertical sectional view taken approximately on line 2 2 of Fig. 1 looking in the direction indicated by the arrow. Fig. 3 is a face view of the wheel side of the dust-guard. Fig. 4 is a central vertical sectional view of Fig. 3, and Fig. 5 is a 50 sectional view taken approximately on line 5 5 of Fig. 4. Fig. 6 is a section on the line 6 6 of Fig. 5. Fig. 7 is an edge view of the invention.

55 Referring to the parts, 1 is a standard journal-box which is provided with the usual

slide-pocket 2, in which is placed the slide or holder 3, comprising the present invention. This holder comprises a rigid member which may be formed of a plurality of plates secured together or from a single plate which is cut to the required form and provided with cavities, hereinafter referred to, though the holder formed of a single plate is preferred, because of its simplicity. The holder 3 is 60 provided with an approximately elliptical central opening 4, at each side of which are formed stop-shoulders 5, the function of which will be hereinafter described. Extending longitudinally of the plates or plate 70 forming the holder 3 are cavities 6, both above and below said central opening, in which cavities are seated the slides 7, which slides are normally pressed toward the center of the opening 4 by means of the Z- 75 shaped springs 8, which bear, respectively, upon the plates 7 and upon the transversely-extending closure 9 of the holder 3.

If the holder is formed of a single piece of material—as of wood, for example—the stops 80 9 may be integral with said plate; but if the holder is formed of a plurality of plates secured together then the stops 9 are preferably separate pieces which are secured at the ends of said plates beyond the cavity 6 in 85 any desired manner, so as to serve as stops for the springs 8 referred to.

To prevent excessive inward thrust of the plates 7, said plates are provided with the elongations 10, which abut against the shoulders 5 when said plates are at their innermost position; but owing to the resiliency of the springs 8 it is evident that the plates 7 may be separated to permit placing the device upon a car-axle 11, and when so placed 95 the springs 8 will at all times keep the said plates in contact with the car-axle, thereby preventing the discharge of dust from the wheel side of the box into the oil-receptacle.

To further guard the oil-receptacle, the 100 plates 3 are provided with packing-strips 12, of felt, upon the lower portion, near the lower edge and near the side edges of the member 3, there being no packing across the upper portion of the member 3 upon the wheel side; 105 but upon the opposite side of the member 3 there is provided a packing 13, of felt, which rests between said member 3 and the rear face of the box 1. Thus if dust should pass between the member 3 and into receptacle 2 110 from the wheel side said dust will only fall upon the axle 11 and thence to the ground;

but if by a chance any dust should be carried below the axle into receptacle 2 the packing-strips 12 will prevent the passage of said dust into the interior of the box 1, and the packing-strip 13, which is placed near the member 3 and said box, will prevent the passage of dust between the member 3 and the oil-chamber from above.

In order to enable me to get the packing-
10 plates 7 into the holder 3, I slit the sides as
at 25, and after the spring 8 and the member
7 have been placed in position strips 26 are
inserted to close up the slots 25 and are held
in place by screws 27, as shown.

15 Having thus described my invention, what
I claim as new, and desire to secure by Let-
ters Patent, is—

1. In a car-axle dust-guard, a holder
formed of a single piece of material having a
20 central opening with cavities at opposite
sides of said opening and formed with stops
extending transversely across said cavities
at the bottom, slides seated in said cavities,
springs within said cavities and bearing on
25 said slides, said holder having slots in its

sides to permit of insertion of the slides
through the sides of the holder, closure-strips
for said holder-slots, and means for main-
taining said closure-strips in said slots, sub-
stantially as shown and described.

2. In a car-axle dust-guard, a holder
formed of a single piece of material having a
central opening provided with cavities at op-
posite sides of said opening, slides seated in
said cavities, springs held within said cavi-
ties to bear against said slides and the bot-
tom wall of said cavities, said holder having
slots in its sides for the insertion of the slides
into the holder, closure-strips for said slots,
means for securing said closure-strips in 40
place, packing-strips on three of the edge por-
tions of said holder upon one side thereof,
and a packing-strip upon the relatively re-
maining edge portion upon the opposite side
of the holder, substantially as shown and de- 45
scribed.
